[57] CLAIM

The ornamental design for a hosiery package, as shown
and described.

DESCRIPTION

FIG. 1 is a perspective view showing the top one end
and one side of the package;

FIG. 2 is an end view thereof;

FIG. 3 is the opposite end view thereof;

FIG. 4 is a top plan view thereof;

FIG. 5 is a first side view thereof;

FIG. 6 is a bottom plan view thereof; and

FIG. 7 is the second side view thereof.

The characteristic feature of my design resides in the
combination of a substantially wedge-shaped container
having a substantially rectangular-shaped side with an
opening and fabric protruding therefrom, all as shown.
